UNITED STATES PATENT OFFICE.

GEORGE H. MURPHY, OF REDDING, CALIFORNIA.

ELECTRIC NEEDLE.

1,127,665.

Specification of Letters Patent.

Patented Feb. 9, 1915.

Application filed May 21, 1914. Serial No. 840,043.

To all whom it may concern:

Be it known that I, GEORGE H. MURPHY, a citizen of the United States, residing at Redding, in the county of Shasta and State 5 of California, have invented certain new and useful Improvements in Electric Needles, of which the following is a specification, reference being had therein to the accompanying drawing.

10 This invention relates to certain new and useful improvements in electric needles to be used for pyrographic, surgical and cauterizing work; the object being to provide a needle which is exceedingly simple and 15 cheap in construction, the point being formed separate and detachable therefrom in order that the same can be removed to allow it to be thoroughly cleaned.

Another and further object of the invention is to provide a needle which is composed of a series of concentric tubular members separated by insulating sleeves to provide a pair of conductors having leads connected thereto through which the electric current 25 passes, the opposite ends of said conductors being connected by a point formed of a single piece of high resistance material, such as nichrome, through which the current is adapted to pass for heating the point.

30 Other and further objects and advantages of the invention will be hereinafter set forth and the novel features thereof defined by the appended claims.

In the drawing—Figure 1, is a longitudinal section through my improved construction of electric needle; Fig. 2, is a section taken on the line 2—2 of Fig. 1; and Fig. 3, is an elevation of the point, showing the members constituting the same, separated.

40 Like numerals of reference refer to like parts in the several figures of the drawings.

In carrying out my invention, I employ a holder comprising a tapering, cylindrical tube 1 preferably formed of fiber in which is 45 arranged a split metal tube 2 preferably formed of brass forming a conductor which is provided at one end, with a lead 3.

The enlarged end of the holder 1 is annularly enlarged interiorly to form a space 50 4 between the tube 2 and the inner wall thereof, forming an annular tapering air jacket so as to prevent the holder from becoming hot at the point at which the same is grasped by the operator in using the same, 55 as will be hereinafter fully described.

Arranged within the brass tube 2 forming

the conductor, is an insulating tube 5 preferably formed of mica in which is arranged a brass tube 6 forming a conductor which is also provided with a lead 7 at one end and to the leads 3 and 7, are adapted to be connected, electric wires leading from a source of supply.

The insulating tube 5 is cut away at one end forming an annular chamber to receive the pen 9, the outer split tubes expanding to allow the point 9 to be inserted and after it has been inserted, the tubes contract so as to hold the same firmly in position, whereby a point holder is formed by means of which, 60 65 the point 9 can be easily and quickly inserted or detached therefrom. It will be seen that the point contacts with the inner and outer conductors.

The point 9 is preferably formed of a 70 single piece of high resistance material, preferably nichrome, having a centrally reduced portion, said point being folded back at the reduced portion upon itself, in order to form a substantially pen-shaped member 75 between which a pen-shaped insulator 10 formed of mica, is arranged; said insulator extending throughout the entire length of the body of the point but terminating short of the point in order to allow the 80 curved end thereof to become red hot by the electric current passing through the same, which is supplied from the conductors 2 and 6. The body of the pen thus formed, is substantially circular in shape and fits between 85 the inner and outer tube of the holder in such a manner that it is securely locked in position therein. By constructing a pen in this manner, the metal of which the pen is formed, is heated until it becomes incandescent which enables the same to be used 90 for various purposes and in such a manner that the operator can readily manipulate the same. In connection with a pen of this construction, a platinum tip 11 can be employed which is secured thereon by any suitable means in order to allow the pen to 95 be used for various purposes.

From the foregoing description, it will be seen that I have provided an electric needle 105 which is provided with a holder formed of a series of concentric tubes, two of which form conductors which are separated by an insulating sleeve in such a manner that the point, when placed between the conductors, 110 will be quickly heated to allow the same to be used.

2
I claim:

1. An electrical instrument, comprising a holder having spaced insulated conductors, a point arranged between said conductors formed of a single piece of metal bent upon itself to form parallel portions, and an insulated member arranged between said parallel portions of said point.
  2. An electrical instrument, comprising a holder composed of an outer shell of fiber material, having spaced cylindrical conductors arranged therein, said conductors being separated by cylindrical insulators, and a point formed of a single piece of metal bent into substantially pen-shape, arranged between said cylindrical conductors.
  3. An electrical instrument, comprising a holder and a point, said point being formed of a single piece of resistance metal bent upon itself to form spaced pen-shaped members, and a pen-shaped insulating member arranged between said members.
  4. An electric needle, comprising a tapering fibrous tube forming an outer shell, a cylindrical conductor arranged within said shell having a lead at one end, a cylindrical insulator arranged within said tube, a second conductor arranged within said insulator having a lead at one end, and a point formed of parallel members insulated apart and connected at one end, arranged between said conductors.
  5. An electrical instrument, comprising a holder having spaced conductors and a point arranged between said conductors, said point comprising two substantially pen-shaped portions connected at one end and separated by a strip of insulation.

6. In an electrical instrument, the combination with a holder having spaced cylindrical conductors, said holder having an annular air jacket at one end, and a pen point for connecting said conductors.
  7. An electrical instrument, comprising a tapering outer shell having an enlarged bore at one end, a split cylindrical conductor arranged within said shell provided with a lead, a cylindrical insulating tube arranged within said conductor, a cylindrical conductor arranged within said insulating tube having a lead at one end, and a pen having its body portion formed of spaced members arranged between said conductors, said body portions being separated by an insulating strip.
  8. An electrical instrument, comprising a holder composed of a pair of concentrically arranged tubular conductors, one of said conductors being split to form a spring pen-gripping member, and a pen arranged between said concentrically arranged tubular conductors.
  9. An electrical instrument, comprising a holder and a point, said point being formed of a single piece of tubular-shaped resistance metal having a reduced portion bent upon itself to form spaced pen-shaped members, and a pen-shaped insulating member arranged between said members.
